LIQUID TREATMENT TANK WITH CONCENTRIC COMPARTMENTS AND WITH DISTRIBUTORS BELOW THE BOTTOM SURFACE

Roy Welter, East Chicago, Ind., assignor to
Graver Tank & Mfg. Co., Inc., a corporation
of Delaware

Application June 14, 1944, Serial No. 540,256

11 Claims. (Cl. 210—55)

1

This invention relates to liquid treatment and particularly to sludge blanket clarifiers and flow distributing means for the same.

It is an important object of this invention to provide improved flow distributing means, particularly for tanks of large area and capacity.

Another important object is to improve such tanks with respect to the power required for flow distribution.

Still other objects and advantages will appear from the detailed description which follows.

In the drawing:

Fig. 1 is a plan view of one embodiment hereof;

Fig. 2 is a partial section through the embodiment of Fig. 1, the section being taken along line 2—2 in Fig. 1 and showing outer parts of the apparatus, at a larger scale than Fig. 1;

Fig. 3 is a view generally similar to Fig. 2 but showing a modified embodiment;

Fig. 4 shows a detail in section along lines 4—4 in Fig. 3;

Fig. 5 shows a similar detail in section along lines 5—5 in Fig. 3, and with a further modification applied; and

Fig. 6 is a further, partial section through the embodiment of Fig. 1, the section being taken along line 6—6 in Fig. 1, and showing inner parts of the apparatus, at a larger scale than Fig. 1.

The treatment tank 10 is defined by a cylindrical concrete wall 11 and a substantially circular, flat concrete bottom 12, and is open at the top. Such tanks as considered herein are generally about 9 to 15 feet deep, and may have a diameter of about 40 to 120 feet.

The raw liquid to be treated enters this tank, through a pipe 13, adjacent the center of the bottom 12. Treated liquid is withdrawn through a launder 14, installed adjacent the top of the tank and drained by an outlet pipe 15. The sludge separated from the liquid settles on the bottom 12 and is scraped into a substantially central sump 16 by a slowly rotating scraper assembly 17; the sump being drained by pipe 18. The scraper assembly 17 may be rotated by conventional means, such as a traction device generally shown at 100, in Fig. 1. Such a device may comprise a carriage 101 having wheels 102 and running on top of the cylindrical concrete wall 12; one of the wheels being suitably actuated by a motor or engine 103 and the carriage being connected with the scraper assembly 17 by structural members 104.

A substantially cylindrical partition 19 is installed concentrically with the tank and extending from adjacent the bottom 12 upwards to a

2

point below the liquid level 20 determined by the overflow launder 14. A narrow, annular, peripheral mixing channel 21 is formed by and between the wall 11 and partition 19. In many instances this channel will be about 12 to 18 inches wide.

A second annular and substantially cylindrical partition 22 is concentrically installed in the tank and extends from above the liquid level 20 downwards to a level below the top of the first partition 19 and above the bottom 12. An inner, annular flocculation channel 23 is defined by and between the two annular partitions 19 and 22. This channel, generally, is at least a few feet wide, in tanks as contemplated herein. An annular, substantially unrestricted slot 23—A is left between the bottom 12 and the lower edge 23—B of the partition 22.

A clarification and sludge filtration zone 24 is defined by and within the inner annular partition 22. Generally, this zone occupies the whole balance of the tank area, and such balance, after deduction of the channels 21 and 23, amounts to the greater part, about 70 to 90 percent, of the total tank area.

In the center of the bottom 12 there is a flow collector or pumping and distributing sump or pit 25, wherein a pumping impeller 26 is rotatably disposed, on a vertical shaft 26—A. This vertical shaft is driven by a motor 27, installed on a platform 28 on top of the tank, above the path of the traction device 100 for the sludge scrapers 17.

The side wall 25—A of the pit 25 is cylindrical, and a number of substantially horizontal pipes

are secured thereto, communicating with said pit. These pipes radiate from this side wall towards the tank wall 11, below the top surface of the bottom 12. They include the raw water inlet pipe 13,

and a plurality of radial distributing pipes 29.

These are preferably formed from vitrified pipe sections, and imbedded in concrete ribs 30 which are integral with the underside of the tank bottom 12 and lying in trenches below this bottom. Vitrified pipe is not very expensive and has a smooth surface, conducive to a low loss of head.

Sometimes, however, preformed concrete pipe will be more economical, especially in very large tanks. Three distributing pipes 29 are shown, but in some instances there may be only one or two, or on the other hand there may be many more, as will be explained herein. With only three distributing pipes uniformly spaced from one another at 120 degrees angular distance, a large sludge sump 16 is conveniently placed in one of the 120 degree corners between two such distributing pipes, ad-

adjacent the distributing sump 25, and the inlet pipe 13 can join the distributing sump between another pair of distributing pipes as shown.

The distributing pipes terminate in an annular duct 31 which is concentric with the tank, and disposed below the annular channel 21 adjacent the tank wall 11 in an annular concrete foundation ring 32. This duct can be formed from similar materials as are used in the pipes 29, and vice versa. Preferably, however, this duct is formed with rectangular cross-section, and integral with the concrete ring 32. The pipes 29 can be formed in similar manner, for uniformity of construction, although preformed pipe sections are generally preferable for these pipes. The ring 32 is integral with the bottom 12, and supports the side wall 11 on the outside of this annular duct 31; a narrow ledge 33 being formed to provide an annular, horizontal step between the inner surface 34 of the duct 31 in the foundation ring, and the inner surface 35 of the tank wall 11. The opposite surface 36 of the inner wall of the annular duct 31 in the foundation ring extends to an upper surface 37 of said ring, on the same level with the ledge 33, which surface 37 may be identical with the top surface of the concrete bottom 12, and the bottom surface of a layer of cement grout 38. This grout forms part of the bottom 12. The outer end of each distributing pipe 29 is located below the surface 37 and above the bottom 38 of the duct 31. This bottom 39 slopes upwardly from the point where a distributing pipe 29 enters the duct towards the next following distributing pipe, so as to make sure that the cross-sectional area of the duct adjacent the distributing pipe is substantially equal with that of the pipe, and the flow velocities in the pipes and duct are substantially equal and uniform. Ahead of the next following distributing pipe, adjacent the juncture between the low and high points of the bottom 39, a transverse concrete wall 40 extends across the duct 31.

On top of the concrete duct 31, a ring of concrete slabs 41 is installed, covering the top of this duct except for numerous, restricted distributing openings 42 in this ring of slabs. These distributing openings are uniformly inclined, preferably about 30 to 45 degrees from the horizontal, the slabs 41 being substantially parallelograms in longitudinal section. The several slots 42 are formed between the slabs, and have uniform area; the several slabs being spaced from one another by integral lugs 43 adjacent the edges on their lower sides, so that the distributing slots 42 in effect are nozzles expanding slightly in the direction of the flow. The total area of the nozzles 42 in a tank is slightly below, to approximately equal with, the total of the cross-sectional areas of the distributing pipes 29, to insure proper distribution.

The slabs 41 may be reinforced by steel wires 44, which may form loops 45 extending above the upper surfaces 46—A of the slabs, in order to facilitate installation of the slabs. The slabs can be loosely and removably placed upon the ledge 33 and surface 37, to facilitate inspection and the cleaning out of the distributing system.

These slabs are preferably quite short so that a great many distributing openings 42 find place along the periphery of the tank. The slabs can be rectangular in plan view, in which event the distributing slots 42 are slightly sector shaped. For all practical purposes, these slabs are rectangular, if a sufficient number of slabs are used. Slabs of identical design and size can be used in

tanks of very different sizes; in addition to the lugs 43, loose spacers (not shown) may be used in obvious manner, to insure slots 42 of proper width.

In the embodiment of Fig. 2, the outer annular partition 19 is made of redwood, which tends to float in the water, and is held against its buoyancy by chains 46 secured to the inside surface 35 of the tank wall 11 by chain holding members 47; the chains being held to the outside of the partition 19 by generally similar holding members 48. Additional chains 49 are installed between the latter holders 48 and additional holders 50 on the inner surface 35 of the tank wall 11, to hold the partition 19 against gravity when the tank is drained. These latter chains are so adjusted as to prevent the partition 19 from contacting the scraper assembly 17 at any time.

Similarly the inner partition 22, as shown, is constructed of redwood and held against buoyancy by chains 51 extending from holders 52 on the inside of the outer partition to holders 53 on the outside of the inner partition; and also held against gravity, to prevent injury to the scraper assembly, by chains 54 extending from the holders 52 to holders 55 on the inner partition. The buoyancy absorbing chains 46 and 51 can be lighter than the weight absorbing chains 49 and 54, since the buoyancy of redwood amounts to less than the weight thereof in air, and this buoyancy is furthermore reduced by the chains and other parts mounted on the partitions. Even the heavier chains 49 and 54 will generally be very thin, all chains being entirely in the nature of tension members, so that these chains offer a minimum of obstruction to the flow passing through the channels 21 and 23. This is important, as will appear from the functional description herein-after.

The aforementioned overflow launder 14 is preferably made from flat steel plates welded together to form troughs of rectangular cross section comprising horizontal bottom plates 56 and vertical side plates 57; the top edges of the side plates acting as overflow weirs 58. A series of rectangular troughs formed in this manner are readily assembled into an annular launder 14 forming a hexagon or other polygon concentric with the tank. This launder is preferably dimensioned so that the area of the clarification zone 24 is separated into two substantially equal parts by the same. This is quite important in large tanks for upward sludge filtration, as will appear from the following.

The launder 14 is secured to the inside of the inner partition 22 by a series of structural brackets 59. Such a structural bracket, particularly the compression part thereof, occupies considerably more area than do the chains 46, 49,

51 and 54. While such area might unduly obstruct the relatively rapid, spiral flows in the relatively small channels 21 and 23, it is quite unobjectionable, adjacent the launder 14, to use such area as the structural brackets inherently occupy, the clarification area being very large and the flow very slow.

Additional buoyancy of the assembly of the inner partition 22 and launder 14 can be provided by attaching a float 60 to the underside of the launder, this float being formed by straight plates 61 welded to the underside of the bottom plate 56 and inclined to form somewhat acute-angled isosceles triangles depending from this bottom, which at the same time is conducive to

a desirable type of upward flow in the clarification zone 24.

In the modified embodiment of Fig. 3 the outer partition is formed by a cylindrical concrete wall 62 resting on the top surface 37 of the annular foundation ring 32, the outer channel 21 being separated from the inner channel 23 by a water stop 63 at the foot of this wall 62.

This construction has the advantage that a more positive flow through the channels is enforced, while in the embodiment of Fig. 2 some liquid may short-circuit from the duct 38 through the gap 64 adjacent the bottom edge of the outer partition 19. On the other hand, the construction of Fig. 2 has the advantage that the scraper assembly 17 may carry a small scraper blade 65 projecting into the outermost channel 21 and removing sludge from the top surface 46 of the slabs 41, where it may have settled particularly after a shut-down of the tank. The amounts of liquid by-passing the channels through the gap 64 can be kept very small and unobjectionable, since the width of this gap, and the configuration thereof, can be restricted as compared with the slot 23-A; that is, it can be such as to force the vastly major portion of the liquid to pass upward through the outer channel 21 and then down through the inner channel 23. The outer channel 21 may have to be somewhat wider in the case of Fig. 2, in order to insure that most of the flow passes through this channel, and somewhat narrower in the case of Fig. 3, in order to counteract sedimentation. A wider channel has the final advantage that the slabs 41 are more easily installed.

Fig. 3 differs also in that structural concrete beams 66 are used, instead of the chains 48 and 51, to hold the inner partition 67. Accordingly, this inner partition can be formed of concrete rather than a floating material like redwood. The concrete beams 66 are preferably installed so as to leave the functional flocculation area of the channels 21 and 23 unobstructed; or in other words, so much of these channels as is required for proper flocculation, in the operation of the tank, is provided below these beams. In some instances, it is desirable that these beams should be installed entirely below the liquid level 20, as shown, whereby the beams act as baffles and a scum release zone 68 is formed between these beams, with a scum removal zone 69 above the same. The scum can be removed from the latter zone by hand or by automatic means (not shown).

Of course, the inner partition 67, which hangs on the concrete beams 66, should be made as light as possible. Generally speaking, the thickness of this partition can be very slight, since it is not necessary that any appreciable liquid head be retained by this partition, and it is not even essential that the partition be absolutely liquid tight. If a scum release and removal zone is required, then ordinarily the baffles 66 required for the same are more than sufficient to support the weight of this thin concrete partition 67.

The launder 14 should also be as light as possible. The steel launder of Fig. 2 tends to be particularly light. However, in some instances, a somewhat heavier concrete construction is preferred, because it is more durable. Accordingly, Fig. 3 shows a launder 14 formed by concrete troughs 70, which have the same approximate outer configuration as the launder and triangular float previously described. At the top of the concrete sidewalls of this trough 70, weir supports may be provided by structural angles 71, having weir

plates 72 adjustably secured thereto. The launders 14 may be supported by concrete brackets 73 held by the inner partition 67.

The basic elements of the apparatus are completed by a source of chemical reagents 78, connected to the central distributing pit 25.

In operation, a variable flow of raw liquids enters the central sump 25 through the pipe 13, while a proportional amount of chemicals is added from the source 78, and continuous agitation and circulation is applied by the pumping impeller 26. This impeller is generally driven by the motor 27 at such a speed that liquid circulates at a considerable velocity through various parts of the tank, regardless whether the incoming flow from the pipe 13 is at a maximum or capacity rate, at an average rate, at a minimum or at zero. Continuous flows as obtained by such circulation are necessary to distribute the liquid under the sludge filter, bed or blanket 74 and to maintain the sludge bed in suspension above the bottom 12; but of course the circulation must not be so rapid, with or without a capacity throughput flow from the source 13, as to raise this sludge bed, or part thereof, sufficiently to cause boil-ups of sludge and entrainment of liquid polluted thereby into the launder 14, or to cause other damage. Thus the rate of rotation of the impeller 26 is quite critical and the motor 27 is preferably equipped with an adjustable speed reducer. Similarly it is most essential that the various parts of the tank should be dimensioned and proportioned so as to provide proper flow and circulation velocities in each of the several parts thereof. Finally, the direction as well as other characteristics of the various flows are important. The following data have been found important in this connection, aside from the major dimensions specified above.

The circulation induced and maintained by the pump 26 passes from the periphery of the pit 25 through the vitreous distributing pipes 29 and annular concrete duct 31, then through the slots 42 at an angle of 30 to 45 degrees from the horizontal, in uniform directions, then spirally and upwardly through the outer channel 21 as a result of this method of injection, then continuing spirally and downwardly through the inner channel 23, then continuing spirally and inwardly over the bottom 12, and finally back into the pit 25. It will be noted that this circulation is a closed one.

In the embodiment of Fig. 3, the flow in the pit 25, distributing pipes 29, annular duct 31, slots 42 and outer channel 21 is properly designated as a mixing flow, and conducted at such mixing velocities as to produce considerable turbulence, for the purpose of initially mixing the circulating liquid with the raw liquid and chemicals added thereto, and subsequently causing collisions between solid particles, to promote their growth into large and heavy flocs. Of course, these constituents are roughly premixed in the pit 25 where desirably, the most rapid mixing velocities prevail, but in order to safely contact every molecule of impurities contained in the water with chemical and physical reagents, reliance is had on continued turbulence in the pipes 29, duct 31, slots 42 and channel 21. Accordingly, the sum total of these elements 25, 29, 31, 42 and 21 is designated as a mixing zone and considerable, but decreasing mixing velocities are maintained therein. In the embodiment of Fig. 2, the mixing zone comprises only the elements 25, 29, 31 and 42.

Referring further to the channel 23 in Fig. 3, this is identified as part of a flocculating zone, and similarly the bottom part 24A of the sludge filtration and clarification zone 24 is properly called a part of the flocculation zone. The velocities maintained in this zone 23 and 24A are slower than the mixing flows, and are called flocculating velocities. In the embodiment of Fig. 2, similar velocities may be maintained also in the outer channel 21, or at least the velocities maintained in that channel may be intermediate between the mixing and flocculating velocities, as a result of which some sludge may settle in this channel, which is removed by the scraper 65.

The spiral flow over the bottom 12 serves the dual purpose of continuing flocculation, and substantially uniformly distributing the liquid below the whole of the large area of the sludge filter 14; it may be called a distributing flow. The effective depth of the zone 24A can be increased by well-known baffles (not shown), if necessary.

In the bulk of the clarification and sludge filtration zone 24, above the lower part 24A traversed by the circulation, a relatively quiescent clarification and sludge filtration is desired, and liquid passes through this zone at what is called a clarifying velocity, and in directions which at least comprise major vertical components by virtue of the aforementioned installation of the overflow weirs, in conjunction with the spiral distributing flow. Of course, this upward flow, in the upper part of the clarification zone, comprises only the equivalent of so much liquid as is introduced through the pipe 13, at any time, and is not augmented by any appreciable circulation; moreover the area of the zone 24 is made very considerable, in order to insure a suitable low velocity.

Typical flow rates in the various zones are as follows.

Zone	For good clarification with heavy lime sludge		For good clarification with light coagulant sludge	
	Approximate minimum rate, in./min.	Approximate maximum rate, in./min.	Approximate minimum rate, in./min.	Approximate maximum rate, in./min.
Mixing	500	3,000	500	3,000
Flocculating	50	1,000	50	750
Clarifying	5	3	5	3

In order to produce such mixing velocities in the aforesaid mixing zone of a tank of large size and capacity, considerable power is required for the motor 27. It is important, for this reason, that no power should be wasted or mis-applied by functionally useless or objectionable hydraulic loads interposed on the mixing zone. Furthermore, it must be considered that all appreciable hydraulic loads, whether in the nature of restricted passages, sudden enlargements, contractions, or otherwise, have a tendency to create small but extremely rapid eddies, which not only consume hydraulic power for desirable mixing functions but also may, in some instances, reach linear velocities at which flocculent particles in the liquid are broken up rather than built up.

In this connection, it is of course distinctly desirable to break up the raw liquid and chemicals into the finest possible particles; but there are limits to the permissible break-up of recirculated flocs. In a tank of the present type, it

has also been found desirable to subject the flocculent particles in the recirculated liquid to a succession of breaking up and building up influences, as a result of which, ultimately, more settleable flocs are formed than otherwise. However, the breaking up of recirculated flocculent particles must not be excessive, because otherwise excessive time is required to rebuild flocs of desired settleability.

Generally speaking, somewhat higher velocities are desirable and economical for the most rapid dispersion of raw chemicals, than are tolerable in view of the fact that this dispersion desirably takes place in the presence of recirculated liquid with flocculent particles therein. For the dispersion of raw chemicals, liquid velocities of about 6000 in./min. are quite economical, and even higher velocities would be desirable if it were not too expensive to provide them. Practically, the maximum mixing velocity must be limited to the amounts shown in the tabulation, in view of the fact that recirculated flocs have to be present, and that newly formed flocs must largely agglomerate therewith.

For ordinary flocculation, liquid velocities about 1.5 ft./sec. or 1080 in./min. are generally considered most desirable, with considerable tolerances both above and below said velocity. Somewhat slower velocities were found to be desirable for flocculation in the presence of large amounts of recirculated sludge, as herein applied. This is particularly true where it is possible to remove sludge settling in the flocculating zone, and this, too, is possible herein.

Thus, both the mixing and the flocculating velocities are preferably lower, herein, than in plants without sludge bed treatment. As a result, the clarifying velocities can be much higher, and the tanks smaller, with equal results.

The power required to obtain suitable flocculating and clarifying flows is practically the same herein as in other, comparable devices. However, in order to generate suitable mixing and spiral distributing flows, less power is required in accordance herewith than otherwise, due to said relatively slow mixing velocities. Furthermore, power is saved and the results are improved by close attention to the following facts and figures.

Assuming a clarifier having a clarifying zone of 80 ft. diameter or about 5000 sq. ft. area, using filtration through a heavy lime sludge, the clarifying throughput flow, at a rising rate of zero to 5 in./m. or zero to 3.1 gal./sq. ft./min. is zero to 15,600 gal./min. or zero to 22 million gallons per day. In some instances, it may be possible to obtain fair clarification with such a flow, combined with a circulation which by itself varies between zero and 22 million gallons per day. Such a variable circulation would be used in order to compensate the throughput flow; and the total mixing flow at all times would comprise about 15,600 gal./min., flowing at a velocity within the range of 500 to 3000 in./min., or about 1 to 4 ft./sec. In the preferred practice, even greater amounts of liquid are uniformly circulated, at such velocities, in order to insure better sludge suspension, to obtain better distribution in the spiral flow over the bottom 12, and to eliminate the necessity for adjustments of the circulating velocity, in normal operation, regardless of variable throughput flows. In such practice, a continuous and uniform circulation of as much as 220 or at least 110 million gallons per day may have to be maintained for best re-

sults, although, in some instances, a continuous and uniform circulation of about 66 million gallons per day is sufficient. The total, maximum mixing flows, then, will amount to 242, 132 or 88 million gallons per day, respectively. A total mixing flow of about 144 million gallons per day, or 100,000 gal./min., may be considered as an average, for such practice.

This tremendous amount of liquid must be pumped through the mixing zone.

The total effective length of the distributing pipes and annular duct, with a clarifying zone of 80 ft. diameter, and a tank of about 92 ft. total diameter is about 330 feet, on the basis of a single 45 ft. distributing pipe for the complete circulation, plus annular duct of 285 ft. length. Some loss of head is caused by this length of piping.

To this must be added, among other things, the entrance loss in the distributing pit, the interior loss of the pumping device, and the losses due to all sudden contractions and sudden enlargements. In piping of the size as generally contemplated herein, each sudden contraction, entrance, and sudden enlargement causes a head loss equivalent to that of about 45, 55 and 100 feet of pipe, respectively, at the flow rates generally considered for this piping. All this raises the loss of head in the tank to that which would be caused by 500 to 600 feet of pipe, at least.

Another most important, potential source of head losses consists in pipe turns, particularly close ones. The closed circulation, inherently, makes a succession of turns totalling at least 360 degrees. Every 90 degree turn, in such piping, is an equivalent of 200 feet of pipe when being close and sharp, and 60 feet of pipe when having a long sweep radius. It must be noted that potentially, this could more than double the inherent loss of head, equivalent to that of 500 feet of pipe. Thus it is a most important object hereof that only a minimum of turns should occur at mixing velocity, and such turns as unavoidably occur at mixing velocity should be smooth and have a long sweep radius.

This is actually achieved. The mixing flow through and from the radial distributing pipes, being one of the particular subjects hereof, is not only short but also devoid of all sharp turns. It makes only one turn, of about 90 degrees, where the distributing pipe joins the peripheral duct.

The additional turns of the liquid, in approaching the small distributing slots 42, branching off from the peripheral duct at 30 to 45 degrees, are so gentle and gradual as to cause only an almost negligible loss of head. This is the case by virtue of the arrangement involving the partitions 40 in the duct 31, adjacent the pipes 29, as a result of which all of these numerous additional turns are made in uniform directions, and no liquid is forced to flow through a sharp return bend. Some appreciable head of course is lost in obtaining proper distribution of the flow, through the slots 42. Since distribution as mentioned is vital, some such loss is unavoidable.

The flow in, through and from the outer channel 21 takes place at a slower rate than that in the distributing pipes and peripheral duct, and is conducive to a much lower head loss. A still further, gradual drop of flow velocity, with resulting conservation of head, takes place at the top of this channel. By virtue of the slow flow rate at this point, where a 180 degree turn or return bend must be made, the additional loss of head is entirely negligible. The same thing is true of the further 90 degree turn at the bot-

tom of the inner channel 23, and the final 90 degree turn adjacent the distributing pit 25.

It will be noted that due to the up-and-down flows in the two channels 21 and 23, the sum total of the successive turns in the circulation is greater than 360 degrees, actually being about 540 degrees. In some constructions, known to the art, still further turns are used adjacent to the central distributing pit, raising this sum total to about 720 degrees. In some instances, the liquid flowing through such further turns adjacent this pit passes at considerable velocities, and considerable additional head is lost as a result. The present arrangement eliminates such additional loss of head, by passing the liquid from the spiral distributing flow directly, downwardly, into the distributing pit.

In the modification shown by Fig. 5, the head conditions are additionally improved by providing a smooth and long-sweep turn from each distributing pipe 29 into the peripheral duct 31. For this purpose there is provided, at the outer end of the distributing pipe and inlet of the duct, a transition duct or nozzle 75, having an inner wall 76 which gradually and smoothly merges into the cylindrical wall of the pipe, as well as into the rectangular wall of the duct, without a sudden contraction and expansion, according to well-known principles of nozzle design. This inner wall 76 is conveniently formed by depositing an annular layer of grout 77 in a suitable recess 78 formed in the concrete of the rib 30 and peripheral foundation 32, and smoothly shaping said grout so as to form said inner wall.

The exact arrangement and dimensions of the distributing pipes 29 and duct 31 must be calculated from the amounts and velocities as specified above, and in doing so, further consideration must be given to structural and functional problems.

Particularly, the peripheral duct 31 must not be made too deep, in relation to the width thereof, in order to avoid an unfavorable cross-section which causes excessive liquid friction and requires costly excavations and foundations. The width of this duct, generally, can not be greater than that of the superimposed, peripheral channel 21, which as mentioned, may be about 12 to 18 inches wide, or possibly somewhat wider in case of Figure 2.

In order to pass said 144 million gallons per day at a mixing velocity of 3 ft./sec., through 10 distributing pipes 29, and continuing arcuate parts of the duct 31, each distributing pipe must have about 3 ft. inside diameter; and the rectangular duct 31, when being 18 in. wide, must be about 5 ft. deep, adjacent the points where the pipes join this duct. Where lower mixing velocities are required, the duct would have to be deeper yet, which is undesirable; in order to compensate, there is required a greater number of pipes, and shorter arcuate duct continuing each pipe, which carries less water, and requires less depth.

The material as well as the labor required for the construction of a tank and equipment as described herein is relatively inexpensive, considering the efficiency, results, and relatively small overall size of the apparatus. It is true, of course, that some extra concrete form work is required for the concrete ribs 30 and duct 31, but the forms required are simple, and of course the concrete or vitrified pipes 29 are most economical, as well as efficient, as compared with any other pipe materials that could be considered.

Reference was had, in the discussion of functional features, above, to "good clarification." It

has become usual, in sludge bed clarifiers, to apply this term if the turbidity of the effluent is safely kept below a certain limit, which generally is specified somewhere within the range of 5 to 25 parts per million. Such an effluent can be produced with the present device, within about 50 to 150 minutes overall detention time for a typical turbid or hard water, with minimum dosage of chemicals, and with shallow excavations for the tank, regardless of the size and capacity thereof. Earlier devices either were limited to greater depth or smaller diameter, or required longer detention or heavier chemical dosage or more power for mixing, or furnished effluents of less than equal quality. All these factors are intimately inter-connected, and improvement as to one can affect all others.

I claim:

1. A liquid treatment tank comprising a substantially circular bottom; a substantially cylindrical wall surrounding said bottom; centrally located, annular wall means extending away from said bottom to form a flow collector, having location in and communication with a lower, central portion of the tank, at least a portion of said collector being located below the surface of said bottom; an outer, substantially cylindrical partition concentrically installed in the tank and extending from below the top thereof downwards to a lower level at least closely adjacent said bottom to define an outer, annular mixing channel between said wall and outer partition; an inner, substantially cylindrical partition concentrically installed in the tank and extending from the top of the tank to a level below the top of said outer partition but above said lower level, to define an inner, annular flocculation channel between said partitions and a clarification compartment within said inner partition; pipe means extending outward from said collector, below the surface of said bottom, and discharging into said mixing channel; means adapted to circulate liquid from said collector through said pipe means, outer and inner channels, over said bottom and back into said collector; means to introduce any newly incoming liquid to be treated and treating reagents into said flow collector; means to remove treated liquid from adjacent the top of said clarification compartment; rotatable means to collect sludge settled on said bottom; means to rotate said rotatable means; and means to remove collected sludge from said tank.

2. A liquid treatment tank as described in claim 1, additionally comprising an annular duct below said mixing channel; apertured division means interposed between said duct and mixing channel; said pipe means discharging into said mixing channel through said duct and the apertures in said division means.

3. A liquid treatment tank, according to claim 2, additionally comprising a plurality of wall members transversely extending across said annular duct, and spaced from one another, whereby said annular duct is subdivided into a plurality of portions; said pipe means comprising a plurality of pipes and each of said pipes communicating with one of the portions of said annular duct.

4. A liquid treatment tank according to claim 2 comprising a transition member interposed between said pipe means and duct, said transition member having smooth inner walls, shaped to avoid sudden contraction, expansion, sharp turns in the liquid flowing from the pipe means into the duct.

5. A liquid treatment tank according to claim 2, wherein said division means comprises individual slabs loosely inserted between said mixing channel and duct.
- 5 6. A liquid treatment tank according to claim 5, wherein said slabs are shaped substantially as parallelograms in longitudinal section; said slabs being longitudinally spaced from one another to provide the apertured division member.
- 10 7. A liquid treatment tank as described in claim 1, wherein at least one of said partitions is buoyant in the liquid under treatment, and which comprises tension means adapted to restrain said partition against buoyancy.
- 15 8. A liquid treatment tank comprising a substantially flat bottom; a wall surrounding said bottom; centrally located, annular wall means extending downwardly from said bottom to form a central pin in said bottom, for flow collection and distribution; annular partition means, concentrically installed in the tank and extending from adjacent the top thereof downwardly to above said bottom, to define an outer flocculation channel, and an inner clarification compartment 25 communicating with said channel adjacent said bottom; distributor pipes extending outward from said central pin, below the surface of said bottom, and discharging into said flocculation channel; a centrifugal impeller disposed in said central pit to circulate liquid from said central pit through said distributor pipes and flocculating channel, over said bottom, back into said central pit; a vertical shaft carrying said impeller and upwardly extending therefrom; a motor 30 mounted at the top of the tank and adapted to rotate said shaft; means to introduce any newly incoming liquid to be treated and treating reagents into said central pit; means to remove treated liquid from adjacent the top of said clarification compartment; rotatable means to collect sludge settled on said bottom; means to rotate said rotatable means; and means to remove collected sludge from said tank.
- 35 9. A liquid treatment tank according to claim 45 8 additionally comprising an annular duct, adjacent said wall surrounding said bottom; an apertured division means interposed between said annular duct and said outer flocculation channel; said distributing pipes discharging into said flocculation channel through said annular duct and through the apertures in said division means for further flow distribution.
- 50 10. A liquid treatment tank according to claim 9 wherein said annular duct is located adjacent the lower part of said wall surrounding said bottom.

11. A liquid treatment tank according to claim 10 wherein said annular duct, said distributor pipes and said central pit are completely incorporated in said bottom.

ROY WELTER.

ROY WELTER

It is hereby certified that error appears in the printed specification of the above numbered patent requiring correction as follows: Column 12, line 19, claim 8, for "central pin" read *central pit*; and that the said Letters Patent should be read with this correction therein that the same may conform to the record of the case in the Patent Office.

Signed and sealed this 11th day of November, A. D. 1947.
